GEORGE A. JOHNSON AND STACY B. HASELTINE, OF CHICAGO, ILLINOIS, ASSIGNEES
TO W. H. MINER, INC., OF CHICAGO, ILLINOIS, A CORPORATION OF DELAWARE

CAR CONSTRUCTION

Application filed November 26, 1928, Serial No. 321,885. Renewed December 5, 1929.

This invention relates to improvements in car construction.

One object of the invention is to provide a combined locking and center pin arrangement for railway car bolsters, which is of exceptional strength and presents exceptionally great cross sectional area to resist shearing, whereby the car truck and body are maintained in substantial connection, especially in the event of collision, to avoid telescoping of the cars of trains.

A more specific object of the invention is to provide a combined center and locking pin arrangement for connecting the body and truck bolsters of a car, having alined center pin receiving openings, including a solid pin headed at opposite ends and having shouldered engagement with the body and truck bolsters, respectively, to prevent separation thereof, the head at one end of the pin or the heads at both ends being cut away at opposite sides and the opposite wall portions of each pin receiving opening of the bolsters being slotted to permit insertion of the pin when in one position, the pin being rotatable to another position to engage the solid portions of the cut-away heads with the shouldered portions of the corresponding bolsters, the pin being locked against rotation with respect to said bolsters by an element having leg portions disposed within the slots of the bolster pin receiving openings and occupying the space between the sides of the pin and the opposed walls of the slots to brace the pin and increase the effective cross sectional area thereof.

Other and further objects of the invention will more clearly appear from the description and claims hereinafter following.

In the drawing forming a part of this specification, Figure 1 is a top plan view of a portion of the body bolster of a railway car. Figure 2 is a vertical transverse sectional view through the body and truck bolsters of a railway car, corresponding substantially to the line 2—2 of Figure 1. Figure 3 is a horizontal sectional view, corresponding substantially to the line 3—3 of Figure 2. And Figure 4 is a horizontally

sectional view, corresponding substantially to the line 4—4 of Figure 2.

In said drawings, the body bolster of the railway car is indicated by the character 10 and cooperates with a truck bolster 11. 55 The bolsters are provided with alined center pin receiving openings and the truck bolster is provided with a pocket 12 at the upper side thereof, in which a bearing block 13 of well known design is seated. The bearing block 13 is provided with a spherical bearing surface 14 at the upper side thereof which cooperates with a spherical bearing surface 15 formed at the bottom side of the body bolster. The bearing block 13 is also 60 provided with an upstanding central portion 16 which engages within an opening 17 formed in the bottom of the body bolster.

In carrying out our invention, we provide the truck bolster with a pin receiving opening 18 and an adjacent pocket 19 which accommodates the head of the combined locking and center pin. The opening 18 is laterally enlarged at diametrically opposite sides, as indicated at 20—20, thereby leaving shoulders 21—21 which form abutment means for the head of the locking pin. The opening in the bearing block 13 is of the same contour as the opening in the bolster 11 and registers therewith.

The body bolster 10 is provided with an opening 22 which is of enlarged cross sectional area adjacent the bottom portion of the bolster, as indicated at 23. At opposite ends of the enlarged portion 23 of the opening, inwardly extending top and bottom flanges or ribs 24 and 25 are provided. The flanges 24 and 25 are cut away at opposite sides, thereby providing openings 45—45, the outer walls of which coincide with opposed wall portions of the enlarged section of the opening 23. Above the flange 24, the opening of the bolster 10 provides a pocket 26 which accommodates the head at the upper end of the locking pin. The opening between the inner edges of the flange 24 and the opening between the inner edges of the flange 25 are of the same diameter and also correspond in diameter to the opening 18 of the bolster 11.

The combined center and locking pin comprises a shank portion 27 having enlargements 28-28 at the bottom end thereof, which form a head cooperating with the shoulders 21 on the truck bolster. At the upper end, the shank 27 is provided with lateral enlargements 29-29 which also form a head of the pin.

The enlargements 28-28 and 29-29 are of such a size as to pass freely through the enlarged portion of the opening 18 of the bolster 11 and also the cut-away portions of the flanges 24 and 25. As will be evident, the locking pin may thus be freely inserted through either the truck or body bolster when the enlargements 28-28 and 29-29 at the opposite ends of the pin are in alinement with the laterally enlarged sections of the opening 18 and the cut-away portions of the flanges 24 and 25 of the bolster 10, and when the pin is rotated, after having been assembled with the bolsters, the enlargements 28-28 and 29-29 are brought into overlapping relation with the shoulders 21-21 and the flange 24, thus interlocking the two bolsters.

To prevent accidental displacement of the locking pin, we provide a U-shaped locking member 30 having depending leg portions 31-31 which straddle the shank of the pin and have flat inner faces 32-32, which embrace the opposite sides of the pin, the pin having the cooperating sides thereof flattened, as indicated at 33, to fit the faces of the leg portions. The connecting top portion of the U-shaped locking member fits over the upper end of the pin and the upper portions of the legs 31-31 are disposed between the enlargements 29-29 of the pin. As most clearly shown in Figures 2 and 3, the leg portions 31-31 extend entirely through the bolster 10 and into the laterally enlarged portions of the opening 18 of the bolster 11, with the lower extremities thereof between the enlargements 28-28 at the lower end of the pin. The upper sections of the leg portions 31 are of such a width and thickness as to fully occupy the cut-away portions of the flanges 24 and 25 and fill the space between the faces 33-33 of the pin and side wall portions of the opening in the bolster 10.

The bottom end portions of the legs 31 which extend into the pin receiving opening of the bolster 11 are reduced in width, as indicated at 34, thereby leaving a certain amount of clearance between the side edges of the same and the transverse wall sections of the enlarged portions of the opening 18. As will be evident, a certain amount of relative angular rotation of the pin and the bolster 11 is thus permitted. The parts are so proportioned that the amount of rotation permitted is sufficient to permit the proper angular turning of the bolsters with

respect to each other when cars are operated on track of maximum curvature encountered in standard railway practice.

In connecting the body and truck bolsters of a car, the pin may be inserted either through the truck or body bolster. When the same is inserted through the truck bolster, the same is passed upwardly through the opening of the truck bolster by first bringing the enlargements 29 into registration with the enlarged portions of the opening 18 and passing the pin upwardly through said opening. It will be understood that at this time the cut-away sections of the flanges 24 and 25 are brought into alinement with the enlarged sections of the opening 18. When the pin has been fully inserted so that the enlargements 29 are disposed above the flange 24, the pin is given a partial rotation to bring the enlargements into overlapping relation with the full sections of the flange 24. This position of the pin is shown in Figures 1 and 2 of the drawing. The locking element 30 is then applied by placing the same over the upper end of the pin with the legs 31 thereof in registration with the cut-away portions of the flanges 24 and 25.

The locking element is then forced downwardly until the section connecting the upper ends of the legs rests on top of the pin and the leg members are engaged within the cut-away portions of the flanges 24 and 25 and the enlarged sections of the opening 18 of the bolster 11. It will be evident that the locking element will thus positively prevent relative rotation between the pin and the bolster 10, and, due to the reduced width of the lower end portions of the legs, will permit the necessary amount of relative rotation between the pin and the bolster 11.

Inasmuch as the legs of the U-shaped member occupy the space between the pin and the opposed walls of the openings in the bolsters, the legs serve to increase the effective cross sectional area of the pin, thereby increasing considerably its capacity to resist shear, which is very important in railway car construction.

When it is desired to insert the retaining pin through the body bolster, the assembling operation is performed in a similar manner to that hereinbefore described, the enlargements 28-28 at the bottom end of the pin being brought into registration with the cut-away portions of the flanges 24 and 25 and the enlarged sections of the opening 18 of the bolster 11. After the pin has been rotated, we bring the enlargements 29-29 in overlapping relation to the flange 24 and the enlargements 28 in overlapping relation with the shoulders 21; the pin is locked by the member 30 by passing the

same over the top of the pin in the manner hereinbefore pointed out.

When it is desired to separate the body and truck bolsters of the car, it is merely necessary to withdraw the locking element 5 30 and rotate the pin until the enlargements 29 register with the cut-away portions of the flanges 24 and 25 and the enlarged sections of the opening 18 and withdraw the 10 pin from either the truck or body bolster.

While we have herein shown and described what we consider the preferred manner of carrying out our invention, the same is merely illustrative and we contemplate all changes 15 and modifications which come within the scope of the claim appended hereto.

We claim:

1. In car construction, the combination with body and truck bolsters having alined 20 center pin receiving openings; of a center pin having a head at one end having shoudered engagement with one of said bolsters, said pin having locking lugs at the opposite end forming a head member having shoudered engagement with the other bolster, the walls of said pin receiving openings being slotted to permit passage of said lugs and said pin being rotatable to bring the lugs thereof in shoudered engagement with 25 the corresponding bolster; and means for locking the pin against rotation with respect to said last named bolster, including a member engaging within the slots of both bolsters and occupying the space between the 30 shank of the pin and the opposed walls of said slots.

2. In car construction, the combination with body and truck bolsters having alined center pin receiving openings; of a center 0 pin having a head at one end having shoudered engagement with one of the bolsters, said pin being provided with locking lugs adapted to cooperate with the other bolster, the walls of the pin receiving openings of 5 said bolsters being cut away to permit passage of the lugs when the pin is in one position, the lugs of said pin being brought out of registration with said cut-away portions and into shoudered engagement with said 10 cooperating bolster when rotated to a predetermined extent; and locking means including legs embracing the shank of the pin and occupying the space between the pin and the walls of the center pin receiving 15 openings of both bolsters at said cut-away sections.

3. In car construction, the combination with body and truck bolsters having alined center pin receiving openings, each of said 20 bolsters being provided with a shoulder adjacent the opening thereof; of a center pin having a shank fitting said openings, said pin having an enlargement at one end forming a head cooperating with the shoulder of 25 one of said bolsters and having a pair of

diametrically disposed enlargements at the other end forming a head cooperating with the shoulder of the other bolster, opposed side wall sections of the pin receiving openings of both bolsters being cut away to permit passage of the diametric enlargements 70 of said pin while said pin is being assembled with the bolsters, said pin being rotatable to a position to bring said diametric enlargements in overlapping relation with the shoulder of said cooperating bolster; and a locking element engaged over the head of the pin cooperating with said last named bolster, said locking element having legs disposed between said diametric enlargements and engaging with the cut-away portions of the walls of the pin receiving openings 75 of both bolsters.

4. In car construction, the combination with body and truck bolsters having alined 80 center pin receiving openings, the opening of each bolster having opposed wall portions outwardly offset with respect to the walls of the main portion of said opening, and each of said bolsters being provided with a shoulder adjacent the opening thereof; of a center pin having a head at each end, one of said heads being formed by lateral enlargements adapted to pass through said offset portions of said openings, the shape 85 of said last named head being such that it may be inserted through said pin receiving openings when in one position but is prevented from passing therethrough when given a partial turn to overlap said lateral 90 enlargements with the shoulder of one of said bolsters, while the head at the other end of the pin is in cooperating relation with the shoulder of the other bolster, the shank of the pin between said heads being 95 of a diameter to fit the main portion of said openings; of a member for locking said pin against rotation with respect to one of said bolsters, said member engaging over the end of the pin provided with the lateral enlargements and having legs embracing and fitting the shank of the pin, said legs extending into the laterally enlarged portions of the 100 openings of both of said bolsters and bearing on the opposite sides of the pin and the offset wall portions of said openings to brace the pin and increase the effective cross 105 sectional area thereof to resist shear.

5. In car construction, the combination with body and truck bolsters having alined center pin receiving openings; of a center pin having enlargements at opposite ends thereof, forming head members, said enlargements being arranged in sets at each end of the pin, the members of each set being disposed at diametrically opposite sides of said pin, the walls of the pin receiving openings being cut away to permit passage of said enlargements and said pin being rotatable to bring the enlargements at opposite 110 115 120 125 130

ends thereof in shouldered engagement with the corresponding bolsters; and means for locking the pin against rotation with respect to one of said bolsters, including a member 5 engaging within the cut-away portions of the openings of both of said bolsters and occupying the space between the shank of the pin and the opposed walls of said cut-away portions.

10 6. In car construction, the combination with body and truck bolsters having alined center pin openings, each bolster being provided with a shoulder adjacent its opening; of a center pin having holding means adjacent opposite ends thereof, the shape of each of said holding means and the cross section of the openings being such that either holding means may be inserted therethrough but is prevented from passing therethrough when 15 given a partial turn; and means cooperating with said pin to prevent turning thereof relative to one of said bolsters to maintain the pin in holding relation with both bolsters.

20 7. In car construction, the combination with body and truck bolsters having alined center pin receiving openings, each bolster being provided with a shoulder adjacent its opening; of a center pin having a head at 25 each end thereof, the shape of each head and the cross section of the openings being such that either head may be inserted therethrough while in one position, but is prevented from passing therethrough when 30 given a partial turn, thereby permitting application and removal of the pin either through the truck bolster or body bolster when said pin is in said first named position; and removable means cooperating with 35 said pin to prevent turning thereof relative to one of said bolsters to prevent disengagement of said pin from said bolsters.

40 8. In car construction, the combination with a body bolster and a truck bolster, said 45 bolsters having alined center pin receiving openings; a locking pin insertible within said openings either downwardly through the body bolster or upwardly through the truck bolster, cooperating means on said bolsters 50 and pin for locking the bolsters together, including means on said pin and both of said bolsters interlocked by relative movement of said pin and bolsters and released by reverse relative movement thereof to a pre-determined extent to permit detachment of 55 the pin, said pin being removable by withdrawing the same either upwardly through the body bolster or downwardly through the truck bolster; and means engageable with 60 the pin for preventing said reverse relative movement thereof to said pre-determined extent, thereby maintaining the locking engagement of the pin and said bolsters, said 65 means when disengaged from the pin per-

mitting displacement of the latter to an extent to allow removal of the same.

In witness that we claim the foregoing, we have hereunto subscribed our names this 23rd day of November 1928.

GEORGE A. JOHNSON.
STACY B. HASELTINE.
